UNITED STATES PATENT OFFICE.

WILSON POLK HARLAN, OF HOLTVILLE, CALIFORNIA.

FLUME-GATE.

1,018,662.

Specification of Letters Patent. Patented Feb. 27, 1912.

Application filed December 26, 1911. Serial No. 667,836.

To all whom it may concern:

Be it known that I, WILSON P. HARLAN, a citizen of the United States, residing at Holtville, in the county of Imperial and

5 State of California, have invented certain new and useful Improvements in Flume-Gates, of which the following is a specification.

The present invention relates to those devices 10 commonly known as flume gates.

An important object of my invention is to provide a flume gate of simple and compact structure, which will be strong, durable, and will not leak.

15 A further object of the invention is to provide a device of the above mentioned character, which may be quickly and easily put in its operative position and which will be easy to operate therein.

20 A further object of the invention is to improve the construction in general of these devices and to provide a flume gate which is highly proficient in fulfilling its function.

Other objects and advantages of the invention will be apparent during the course 25 of the following description.

In the accompanying drawings forming a part of this specification and in which like numerals are employed to designate like 30 parts throughout the same, Figure 1 is a front elevation of the flume gate, Fig. 2 is a vertical sectional view taken on line 2—2 of Fig. 1, Fig. 3 is a horizontal sectional view taken on line 3—3 of Fig. 1, Fig. 4 is 35 a similar view taken on line 4—4 of Fig. 1, and, Fig. 5 is a fragmentary front elevation of the upper portion of a plate forming the body portion of the flume gate.

In the drawings wherein is illustrated a 40 preferred embodiment of my invention, the numeral 1 designates a strand pipe, preferably formed of concrete or the like, for receiving a tube or flume 2, provided at its outer end with an outwardly extending annular flange 3.

The numeral 4 designates the body portion of the flume gate and is in the form of a plate provided with a central opening 5, for receiving the flume 2, as shown. The 45 flange 3 engages upon the outer face of the plate 4 and holds the same in firm engagement with the strand pipe 1. At its lower end the plate 4 extends below pipe 1 and is bent upwardly for forming a curved receiving flange 6, as shown. The flange 6 is provided with openings 6', for a purpose to be

described. Disposed at the upper end of the plate 4 is a rigid substantially rectangular open frame 7, within which extends the plate 4.

60 The plate 4 is provided at its upper end with a flap 8, which is bent downwardly about the rear side 9 of the open frame 7, as shown. This flap may be soldered or otherwise rigidly secured to the open frame. 65 The plate 4 is bent at its vertical edges, forming vertical curved receiving flanges 10, which are also disposed within the open frame 7. The forward walls of these curved flanges are provided with upwardly extending flaps 11, which are bent forwardly and downwardly about the forward side 12 of the open frame 7, and may be soldered or otherwise rigidly secured thereto. The forward walls of the vertical receiving flanges 70 10 preferably terminate at points above and spaced from the horizontal receiving flange 6.

75 The numeral 13 designates a slide plate adapted for operation through the frame 7 and in the receiving flanges 10 and 6. Attention is called to the fact that the plate 4 and the receiving flanges are formed of sheet metal and accordingly yieldingly hold the slide plate in firm engagement with the flange 3 of the flume 2. The slide plate 13 has a tongue 14 stamped from the upper portion of its material and bent to form a handle or other means by which the slide plate may be moved. The forward side 12 of the open frame 7 is provided with an inwardly extending clamping tongue 15, extending between the flanges 10 and engaging the slide plate 13 to hold the same in proper engagement with the flange 3.

80 In the use of my improved flume gate material may be discharged through the flume 2 by raising the slide plate 13. The openings 6' in the lower receiving flange 6 prevent the accumulation of mud or the like 85 in the flange 6.

90 It is obvious that the flume gate as a whole is of simple construction, is strong, durable, and will not leak.

95 I wish it understood that the form of my invention herewith shown and described is to be taken as a preferred example of the same and that certain changes in the shape, size, and arrangement of parts may be resorted to without departing from the spirit 100 of the invention or the scope of the subjoined claims.

Having thus described my invention I claim:

1. The combination with a flume, of a plate provided with an opening and connected with said flume, said plate being provided with receiving flanges, an open frame connected with the upper end of the plate and with the receiving flanges, and a slide plate operating through the open frame and 10 the receiving flanges.

2. The combination with a flume, of a plate having an opening formed therethrough and connected with said flume, said plate being provided with vertical receiving 15 flanges, an open frame receiving the plate and the flanges and connected with the same, a slide plate operating through the open frame and the receiving flanges, and an inwardly extending clamping tongue formed 20 upon the forward side of the open frame and engaging the slide plate.

3. The combination with a flume, provided at its discharge end with an outwardly extending flange, of a plate having an opening 25 for receiving the flume and to be en-

gaged by the outwardly extending flange, said plate being provided with spaced vertical receiving flanges and a lower horizontal receiving flange having openings formed therethrough to prevent the accumulation of 30 mud or the like, and a slide plate for operation within said receiving flanges.

4. The combination with a flume, having at its discharge end an outwardly extending flange, of a plate provided with an opening for receiving the flume, and to be engaged by the outwardly extending flange, said plate being provided with upstanding receiving flanges, an open frame receiving the plate and flanges, said plate and flanges 35 having flaps bent about the open frame for forming suitable connection between the same, and a slide plate operating in the receiving flanges.

In testimony whereof I affix my signature 45 in presence of two witnesses.

WILSON POLK HARLAN.
